(57) **CLAIM**

The ornamental design for a table, as shown and described.

DESCRIPTION

FIG. 1 is a left front perspective view of a table showing my new design;

FIG. 2 is a front elevational view, the rear view being a mirror image thereof;

FIG. 3 is a side elevational view, the opposite side being a mirror image thereof;

FIG. 4 is a top view thereof; and,

FIG. 5 is an enlarged partial perspective view of a corner section thereof.

The bottom view is not shown and forms no part of the claimed design. The dashed lines represent environmental elements only and form no part of the claimed design.
